CARBURETOR

William B. Parker, Manchester, Tenn.

Application July 19, 1934, Serial No. 736,077

14 Claims. (Cl. 261—49)

My invention relates to improvements in carburetors for internal combustion engines.

An important object of the invention is to provide a carburetor which will effect an economy in the use of fuel.

A further object of the invention is to provide a carburetor which will produce an improved explosive charge, whereby greater power is obtained.

A further object of the invention is to provide a carburetor so constructed that the automatic vacuum tank or fuel pump is eliminated and the liquid fuel properly fed to the carburetor.

A further object of the invention is to provide means for supplying moisture or water vapor to the explosive charge.

A further object of the invention is to provide a device for use in connection with a carburetor for supplying moisture or water vapor to the explosive charge.

20 A further object of the invention is to provide a carburetor having means to supply a reduced explosive charge to cylinders of the engine, when the engine is idling, and an increased amount of the explosive charge, as the engine increases 25 the speed, and in proportion to such increase in speed.

A further object of the invention is to provide a carburetor of the above mentioned character, which is of simple construction, strong, durable, 30 and is not liable to derangement.

Other objects and advantages of the invention will be apparent during the course of the following description.

In the accompanying drawings forming a part 35 of this application and in which like numerals are employed to designate like parts throughout the same,

Figure 1 is a perspective view of a carburetor embodying my invention.

40 Figure 2 is a longitudinal section taken substantially on line 2—2 of Figure 1.

Figure 3 is a transverse section taken on line 3—3 of Figure 1.

45 Figure 4 is a similar view taken on line 4—4 of Figure 1.

Figure 5 is a longitudinal section taken on line 5—5 of Figure 1.

Figure 5^a is a transverse section taken on line 5^a—5^a of Figure 2.

50 Figure 6 is a perspective view of the draft actuated element and valve operated thereby.

Figure 7 is a perspective view of a carburetor embodying a modified form of the invention.

55 Figure 8 is a similar view of a carburetor em-

bodying a still further modified form of the invention.

Figure 9 is a perspective view of a portion of the carburetor employed in connection with a separate carburetor for supplying moisture to the 5 charge, and,

Figure 10 is a plan view of the device shown in Figure 9.

Attention being called first to Figures 1 to 8 inclusive, the numeral 15 designates the main 10 casing or pipe, which may be vertically arranged, as the present carburetor is illustrated as a down-draft carburetor, while the invention is not necessarily restricted to the down-draft feature. The vertical casing 15 has its upper end open and 15 its lower end is provided with a coupling flange 16. The numeral 17 designates the intake manifold of an internal combustion engine having a coupling flange 18, arranged opposite the flange 16, for a purpose to be described. Mounted within 20 in the upper portion of the main air inlet pipe 15 is a throttle valve 19, which turns in the direction of the arrow, Figure 2, when opening. This throttle valve is mounted upon a transverse shaft 20, extending to the exterior of the casing 15 25 and having a lever 21 attached thereto, to turn the shaft. The lever 21 has an adjustable stop element or screw 22, carried thereby, to engage with a stop lug 23. The stop element 22 may be adjusted so that there is a slight passage between 30 the throttle valve 19 and the inner wall of the main air inlet pipe 15, when the throttle valve is in the closed position. The lever 21 also has an adjustable stop element or screw 24 carried thereby, and arranged near its opposite end, and 35 this stop element or screw engages the same stop lug 23 to limit the opening movement of the throttle valve 19 so that it does not assume a completely vertical position when shifted toward such open position, but will be slightly inclined, 40 as shown by dotted lines in Figure 2, thereby producing a slight choking effect when shifted to the extreme open position. The lever 21 is connected with the gas lever or accelerator in the automobile, as is the common practice.

45 The numeral 25 designates a block constituting the body portion of the carburetor, and this block 25 is arranged between the coupling flanges 16 and 18 and is clamped thereto by bolts 26 or the like, with suitable packing or gaskets 27 between 50 these parts. The block 25 is provided with a main vertical opening 28, in substantial alignment with the bores of the pipe 15 and the intake end of the intake manifold 17, as shown. The block 25 is provided, adjacent to the main open- 55

ing or passage 28, with cylindrical recesses 29, Figure 10, to receive the ends of a cylindrical shaft 30. This shaft receives thereon a cylindrical sleeve 31, having transverse ports 32 and 33, which 5 also extend through the shaft 30. The sleeve 31 is clamped or locked upon the shaft 30 by a set screw 34 or the like. The sleeve 31 and the portion of the shaft 30 upon which it is mounted constitute a pivoted valve body 31'. Rigidly attached to the sleeve 31 and preferably formed integral therewith, is a draft actuated element or valve 35, which is adapted to substantially cover the main opening or passage 28 when in the upper or closed position and its free end portion 10 will then engage beneath a shoulder 36. The function of the shoulder is to form a tighter joint with the draft actuated element or valve 35 and to limit its upward movement, particularly against back-firing action.

20 The block 25 is provided with a longitudinally extending charge supply port 37, which leads to the valve body 31'. When the valve body is in the closed position, with the draft actuated element 35 closed, such valve body covers the outlet end 25 of the port 37, but as the element 35 is swung downwardly and the valve body 31' turned with it, transverse port 32 is brought into communication with the port 37, and the mixture of air and gas will be supplied into the passage 28, above 30 the draft actuated element 35. The port 37 has its rear end portion enlarged, as shown at 38, and this enlarged portion is internally threaded to receive a tubular nipple 39, having a reduced bore 40, to regulate the entrance of air into the 35 port 37. If desired, a nipple 39, having a different sized bore 40, could be substituted to admit more or less air, as found desirable. The numeral 41 designates an auxiliary block, the forward end of which is arranged beneath and adjacent to the 40 rear end of the block 25 and is provided with a recess or chamber 42. The block 41 is rigidly attached to the block 25 by means of a screw 43, provided with a washer 44, and a washer 46 is arranged between the blocks 41 and 25, as shown.

45 The screw 43 has screw-threaded engagement within the opening 47 and the upper end of the screw 43 terminates substantially centrally within the enlarged bore 38. The screw 43 has a portion thereof tubular, which is afforded by a port 48 formed therein, which extends through the upper end of the screw and laterally through the same, substantially centrally of the recess or chamber 42. The rear end of the block 25 is provided with a screw-threaded boss 49, receiving the 50 screw-threaded portion 50 of an adjustable needle valve 51, adapted to project within the outlet end of the bore 48 of the tubular element or screw 43, to regulate the amount of gasoline fed into the enlarged bore 38 and to also atomize 55 or spray the same. The needle valve is held against accidental displacement by means of a coil spring 52, surrounding the same, and engaging a transverse pin 53, as shown. Leading into the recess or chamber 42 is a longitudinal port 54, formed in the block 41, and the rear end of this longitudinal port leads into a recess or chamber 55, formed in the block 41 and an upstanding transverse portion 56 thereof. The block 41 is provided upon its lower face and generally centrally thereof, with a cylindrical recess 57, receiving a washer 58, which is engaged by the upper end of a suction bulb or receptacle 59, preferably formed of glass. This suction bulb or receptacle 60, the upper ends of which are pivoted with the 65 block 41, as shown at 61. A pin 62 is rigidly attached to the lower closed end of this bulb, and this pin is screw-threaded for receiving a clamping nut 63, acting against a hollow washer 64, adapted to engage with the bottom of the bulb 5 or receptacle 59 and hold the same in place. The recess or chamber 55 is arranged above the bulb 65 or receptacle 59 and the bottom of this recess or chamber has a screw-threaded opening for receiving the upper screw-threaded end 65 of a tube 66, which depends below the block 41 and enters the bulb or receptacle 59 and preferably terminates near the bottom of the bulb or receptacle, and should at least terminate at an elevation beneath the minimum level of the liquid fuel 10 within the bulb or receptacle 59. At its upper end the tube 66 projects into the recess or chamber 55 and is provided with a valve seat 67, for engagement with an upwardly opening check valve 68, preferably formed of fibrous material, such as cork, fiber or the like, although the same may be formed of metal. This check valve is urged downwardly toward its seat by a compressible coil spring 69, engaged by an adjustable screw-threaded plug 70, operating with a screw-threaded opening 71 and having a washer 72 arranged beneath the same. The block 41 is further provided with a rear longitudinal port 73, the forward end of which turns downwardly, as shown at 74, and passes through the bottom wall 30 of the recess 57, and hence leads into the top of the bulb or receptacle 59. The liquid fuel, such as gasoline is supplied to the port 73 through a coupling 75 having connection with a pipe (not shown) which leads into the gasoline tank of 35 the automobile. In order that my carburetor will not flood, it is necessary that the carburetor be arranged at an elevation above the gasoline tank. The gasoline is withdrawn from the bulb or receptacle 59 by the suction within the intake manifold 76, such gasoline passing through the port 54, discharging at the needle valve 51 and being sprayed or atomized at this point and mixed with the air passing through the nipple 40 and then passing through the port 37 to the intake manifold. As the tube 66 has its intake end beneath the level of the gasoline within the bulb or receptacle 59, this gasoline forms a seal with the tube 66, and as the level of the gasoline descends, it creates a partial vacuum at the top of the receptacle or bulb 59, drawing in gasoline from the tank through the port 73. The vaporized fuel is supplied in the intake manifold when the engine is speeded up beyond idling but is not supplied to the intake manifold when the engine is idling, 45 as the valve body 31' then has its port 32 in the closed position. Separate means are provided to supply the charge to the intake manifold, for driving the engine while idling. The separate means includes a lug or post 76 having a chamber 77, Figures 2 and 5, which is in communication with a tube 78, connected with a coupling 79. This coupling 79, Figure 3, is in communication with a recess 80, having a vertical tube 81 leading into its lower end, and this tube 81 extends into 60 the bulb or receptacle 59 and has its lower end preferably terminated at the same elevation as the lower end of the tube 66. The upper end of the tube 81 within the chamber 80 has a valve seat 82, for engagement with an upwardly opening check valve 83, preferably formed of fibrous material, such as cork, fiber, although the same may be formed of metal. This check valve is urged downwardly by a compressible coil spring 84 engaging a plug 85, having screw-threaded 65

70

75

70

75

engagement within a screw-threaded opening 86. The function of the check valves 68 and 83 is to prevent the back flow of air into the bulb or receptacle 59, and hence the breaking of the suction therein. Thus when the gasoline is being supplied to the intake manifold for high speed, the check valve 83 prevents back suction through the idling gasoline supply means, and when the gasoline is supplied for idling of the engine, check valve 68 will prevent the back flow of air through the high speed gasoline supplying means. The chamber 77, Figure 2, has communication with a port 87, which leads into the main air supply pipe 15 at a point beneath the throttle valve 19, whereby the charge is supplied to the intake manifold when the throttle valve is closed and the engine is idling. Air is supplied to the chamber 77 through a port 88, Figure 5a, leading into one end of the chamber 77, and this supply of air is regulated by an adjustable needle valve 89. The gasoline entering the chamber 77 is sprayed or atomized by passing through the nozzle 90, and then becomes vaporized and mixed with the incoming air through the port 88, the gaseous mixture discharging through the port 87. It should be noted that the supply of the idling charge is entirely independent of the rotary valve body 31'.

Means are also provided to supply moisture or water vapor to the intake manifold. To accomplish this, the block 25 is provided in its rear portion with a vertical chamber 91, and a threaded tubular coupling 92 engages within the lower end of this chamber and has connection with a pipe 93, which leads to a water tank, disposed at a level below the chamber 91 to prevent flooding. The tubular coupling 92 is provided at its upper end with an outlet or valve seat 94 for coaction with an adjustable needle valve 95, having screw-threaded engagement within a post 96 and extending to the exterior of the top of the block 25. The needle valve 95 may be employed to regulate the amount of water supplied into the chamber 91, and also to atomize or spray this water, and may be also manipulated to completely cut off the supply of water when desired. Air is supplied into the rear side of the vertical chamber 91 through a rear longitudinal port 97, and the amount of air may be regulated by a pivoted plate valve 98, Figure 1. The air entering the chamber 91 mixes with the atomized water and becomes saturated or laden with the same. Having communication with the forward side of the chamber 91 is a longitudinal port 99, extending through the block 25 and leading to the passage 28, at a point whereby it may be brought into and out of registration with the transverse bore 33 of the swinging valve body 31'. When the draft actuated member 35 is in the closed position, the supply of fuel through the port 32 and the supply of moisture through the port 33 are both cut off.

The description thus far given is common to the three forms of the invention shown in Figures 1 to 7 and 8, and also 10.

Attention is now called to Figures 1 to 6 inclusive, showing the first or preferred form of the invention. In connection with this first or preferred form of the invention, means are provided for turning the valve body 31'. This means comprises a cylinder 100, having a pipe 101 leading into its upper end, and this pipe leads into the main air supply pipe 15, at a point beneath the throttle valve 19. The cylinder 100 is supported by a bracket 102, which may be rigidly attached to the flange 16. Mounted to reciprocate with-

in the cylinder 100, is a plunger 103, having pivotal connection with a connecting rod or pitman 104, the lower end of the cylinder 100 being open. The lower end of the connecting rod 104 is pivotally connected at 105 with a lever 106, which is rigidly mounted upon one end of the shaft 30. A retractile coil spring 107 is attached to the lever 106, to swing the same downwardly and the opposite end of this spring is attached to a stationary hook or lug 108. A choke lever 109 is pivotally mounted upon the shaft 30, upon the inner side of the lever 106, and has a laterally projecting leaf or extension 110, arranged to engage above the lever 106 and forwardly of its pivot. A rod 111 is pivotally connected with the choke lever 109, and extends to the dash of the automobile or other convenient point. When the choke lever 109 is swung rearwardly, it will depress the lever 106, but the lever 106 may move downwardly without shifting the choke lever.

The operation of the first or preferred form of the carburetor is as follows:

When the engine is not running and is cold, the throttle valve 19 is closed and the spring 107 swings the lever 106 downwardly, and the draft actuated element 35 is in the lower or opened position, since there is no suction in the pipe 15 beneath the closed throttle valve. With this adjustment of parts, the port 32 is in registration with port 37, and the port 33 is in registration with the port 99, and hence the gaseous charge and the moisture may be drawn into the intake manifold 17. The engine is now cranked and upon starting will create a suction within the intake manifold and pipe 15 beneath the closed throttle valve 19. It is thus seen that the maximum amount of explosive charge is fed to the intake manifold upon starting. When the engine is cranked, the vaporized fuel is also drawn into the pipe 15 beneath the throttle valve 19 through the port 87, and this supply of fuel continues during the idling of the engine. When the suction is created in the pipe 15 beneath the throttle valve 19 upon the start of the engine the plunger 103 rises and overcomes the action of the spring 107 and thereby closes the draft actuated element 35, and the engine may now idle upon the fuel supplied through the port 87. Should the engine stop after starting, it may be necessary to retain the valve body 31' and draft actuated element 35 in the opened position for a short period, to supply an abundance of fuel to the engine to insure proper running until it has warmed up sufficiently. This is accomplished by pulling the chock rod 111 rearwardly, which will swing the choke lever 109 rearwardly and depress lever 106 and hold this lever depressed until the choke lever 109 is released. The engine being now suitably warmed up and the choke lever 109 released, plunger 103 and associated elements will return the valve body 31' and draft actuated element 35 to the closed position, and the engine will continue to idle on the fuel supplied through the port 87. To speed up the engine, the throttle valve 19 is swung toward the opened position and this will reduce the suction in the pipe 15 beneath the throttle valve, whereby the spring 107 and the down draft of air through the pipe 15 impinging upon the draft actuated element 35, will turn the valve body 31' toward the opened position, in opposition to the suction action upon the top of the plunger 103. The ports 32 and 33 are now brought into communication with the ports 37

and 99 and the explosive charge and moisture drawn into the intake manifold 11, in the presence of the incoming air. As the engine speeds up, the suction within the pipe 15 beneath the 5 throttle valve 19, which is now partly or wholly opened, is transmitted to the top of the plunger 103, and the lifting action of this suction on the plunger 103 is opposed to the downward force which the draft of air produces by impinging upon the draft actuated element 35, the draft forcing the element 35 downwardly toward the complete opened position. As the velocity of the draft increases, which is produced by the further opening movement of the throttle valve. The 10 speed of the motor is controlled by the extent of opening of the throttle valve 19, and the extent of opening of the draft actuated element 35 is controlled by the speed of the engine which creates the draft. When the engine slows down 15 upon the swinging movement of the throttle valve 19 toward the closed position, the velocity of the draft of air is reduced, the degree of suction within the pipe 15 beneath the throttle valve increases, and plunger 103 moves upwardly to 20 swing the draft actuated element upwardly, which in turn moves the valve body 31' toward the closed position, thereby reducing the supply of the explosive charge and moisture in proportion to the speed of the engine. When the throttle valve 19 is opened to any considerable extent, quickly, the vacuum within the pipe 15 beneath the throttle valve is at once broken, and the spring 107, before the velocity of the draft has increased to any considerable extent, will 25 quickly shift the draft actuated element 35 to the lowermost or opened position. This will supply the maximum amount of the explosive charge to the intake manifold, thus imparting to the engine a quick pick-up. As the degree of 30 vacuum increases in the pipe 15 beneath the throttle valve 19, it acts upon the top of the plunger 103, tending to elevate the same, which in turn will swing the draft actuated element 35 upwardly, and this upward swinging movement 35 is opposed by the velocity of the downwardly travelling air draft impinging upon the element 35. These two forces therefore work in opposition, the suction force increasing as the throttle valve approaches the closed position and the 40 velocity of the draft decreases and vice versa. It 45 is thus seen that means are provided which automatically meters or measures the volume of the explosive charge supplied to the engine in proportion to the speed of the engine.

50 In Figure 7, I have shown the second modified form of the carburetor. In connection with this form of carburetor the cylinder 100, pipe 101, connecting rod 104 and spring 107 are dispensed with and there is no opening in the pipe 105 for the pipe 101. A retractile coil spring 112 is arranged above the lever 106 and is connected therewith and may be attached to the shaft 20 of the throttle valve or to any other stationary object. The spring 112 serves to swing the lever 106 upwardly and thereby turn the shaft 30 in a direction to swing the draft actuated element 35 upwardly. All other parts of the carburetor remain identical with the first form of the carburetor. The operation of the second form of the carburetor is as follows:

55 With the engine at rest, or cold, the operator draws the choke rod 111 rearwardly, which swings the choke lever 109 rearwardly and turns the shaft 30, which in turn swings the draft actuated element 35 downwardly to the opened position.

60 sition and also turns the valve body 31' so that ports 32 and 33 register with ports 37 and 99, respectively. The engine is now cranked and the maximum supply of the charge will be drawn into the cylinders, the throttle valve 19 remaining closed to afford a rich mixture. As soon as the engine starts up the choke rod 111 is released and the spring 112 will return the draft actuated element 35 and associated elements to the closed position and the engine will idle upon the charge received through the pipe 78. As the throttle valve 19 is moved toward the opened position the velocity of the down draft of the air through the pipe 15 is increased, this draft impinging upon the element 35 and shifting the same toward the opened position, the extent of opening movement of the element 35 corresponding to the extent of opening movement of the throttle valve. As the draft actuated element 35 opens, ports 32 and 33 move into communication with ports 37 and 99, thus supplying the explosive charge to the intake manifold, with the throttle valve partly or wholly opened. It is thus seen that the draft actuated element 35 does not instantaneously drop to the lowermost position when the throttle valve is first partly opened as occurs with the first form of the invention, and the first form of the invention has the advantage of a quicker pick-up.

65 In connection with the third form of the carburetor, shown in Figure 8, with relation to the first form of the carburetor, shown in Figure 1, the cylinder 100, pipe 101, connecting link 104 and spring 107, are omitted. The pipe 15 has no opening for the pipe 101. The same lever 106 is rigidly mounted upon the shaft 30 and the same choke lever 109 is provided. The shaft 20 of the throttle valve 19, Figure 8, has a lever 113 rigidly secured thereto, and this lever has pivotal connection at 114, with the link 115. The link 115 is provided in its lower end with an elongated slot 116, receiving a pin 117, attached to the forward end of the lever 106. The lever 106 is swung upwardly by a retractile coil spring 118, which may be attached to the pin 117 and to the end of the lever 113 or to any other suitable stationary member or projection. All other parts of the carburetor shown in Figure 8 are identical with the first form of carburetor, as shown in Figure 1.

70 The operation of the form of carburetor shown in Figure 8 is as follows:

75 When the engine is at rest and cold, to start the engine the choke rod 111 is moved rearwardly to swing the choke lever 109 rearwardly and this choke lever then swings lever 106 downwardly, which in turn swings the draft actuated element 35 downwardly to the opened position and turns the valve body 31' to bring ports 32 and 33 into communication with ports 37 and 99, whereby a 80 large volume of the explosive charge is fed to the intake manifold and this occurs while the throttle valve 19 remains closed, thereby affording a rich mixture for starting. The downward movement of the lever 106 does not move the pin 117 is normally at the top end of the slot 116, and moves downwardly in this slot without moving the link 115 downwardly. When the choke lever 109 is released, the spring 118 will return the draft actuated element 35 and associated elements to the closed position, and the engine may then idle upon the fuel drawn through the pipe 78. To speed up the engine the throttle valve 19 is shifted toward the opened position, and in 75

order that there may be an immediate supply of fuel to the engine for a quick pick-up, the link 115 will now be moved downwardly and the top end wall of the slot 116 will engage the pin 117 and mechanically shift the lever 106 downwardly, opening element 35 and turning the valve body 31' to the opened position. As soon as the engine speeds up, the velocity of the draft increases, and this draft impinges upon the element 35, swinging the same downwardly to a great extent or maintaining the same in a partly opened position. The extent of opening of the element 35 will correspond to the speed of the engine and velocity of the draft, and hence the valve body will supply a corresponding increased amount of fuel to the engine as its speed increases. When the throttle valve 19 is again swung toward the closed position, the link 115 rises, and as the velocity of the air impinging upon the element 35 decreases, the spring 118 will swing the element 35 and associated elements upwardly.

In Figures 9 and 10, I have shown a unit of my carburetor used as a gas saver in connection with a standard type of carburetor. This unit includes the block 25. The fuel supply port 37 is closed at its two intakes, by a plug 119, which is substituted for the air jet 40, and a similar plug is substituted for the tubular element or bolt 43 and closes the opening 47. The needle valve 51 is preferably removed and a plug 120 substituted therefor. The air supply port 97 and the water supply pipe 93 and associated elements remain identical, and also the shaft 30, valve body 31' and draft actuated element 35. The same lever 106 is attached to the shaft 30. The block 25 is applied to the same intake manifold 17, but the pipe 15 and associated elements is omitted, and a down-draft carburetor 121, of any well known or preferred type, is employed with the block 25 arranged between the intake end of the manifold 17 and the outlet end of the carburetor 121, such block being held in place by the bolts 26, which extend through the flange 18 and a flange 122 of the carburetor. The lever 106 is swung upwardly by a retractile coil spring 123. As before stated, the carburetor 121 is preferably of the down-draft type and is of any well known or preferred construction, the same embodying a choke valve 124, actuated by a crank 125, and a throttle valve 126 actuated by a crank 127.

The operation of the gas saver is as follows:

With the engine at rest and cold, to start the engine, the choke valve 124 is closed and the throttle valve 126 partly opened, the spring 123 now holds the draft actuated element 35 and associated elements in the closed position. When the engine is cranked, the rich mixture is drawn into the cylinders and the engine started. Upon the starting of the engine, there may be a partial opening of the draft actuated element 35 or the element may open and close to some extent. As soon as the engine has started, the choke valve 124 is released and is returned to the opened position, whereby the suction within the intake manifold will create a down draft of air, impinging upon the element 35, and serving to shift the same to the opened position. As the speed of the engine increases, the velocity of the draft of air increases correspondingly, and the element 35 and valve body 31' are moved corresponding distances toward the complete opened position. When the draft actuated element 35 moves toward the opened position, port 33 is brought into communication with port 99, and the air laden with moisture passes through the

port 33 and is drawn into the main passage 28, and is mixed with the charge from the carburetor. It is thus seen that the device will supply an additional amount of air laden with water to the previously formed charge from the carburetor, and the amount of additional air thus supplied will be supplied in an increased volume corresponding to the increase in the speed of the engine. It is preferred to use the device for supplying air laden with moisture to the passage 28, but I contemplate closing off the supply of water and using the device to supply an additional amount of air only, to the passage 28.

It is to be understood that the forms of my invention herewith shown and described are to be taken as preferred examples of the same and that various changes in the shape, size and arrangement of parts may be resorted to without departing from the spirit of the invention or the scope of the subjoined claims.

Having thus described my invention, what I claim is:

1. In a carburetor, a casing, a throttle valve for controlling the volume of air entering the casing, a draft actuated element disposed in the path of travel of the draft passing through the casing, means for introducing fuel into the casing inwardly of the throttle valve and operated by the draft actuated element, a suction operated device connected with the draft actuated element and adapted to shift the same in an opposite direction to the movement thereof caused by the draft, and a spring to move the draft actuated element in the direction of the draft.

2. In a carburetor, a casing, a throttle valve for controlling the volume of air entering the casing, a draft actuated element disposed in the path of travel of the draft passing through the casing, means for introducing the fuel into the casing inwardly of the throttle valve and operated by the draft actuated element, a suction operated device connected with the draft actuated element and adapted to shift the same in an opposite direction to the travel of the draft, and manually operated means connected with the draft actuated element and adapted to shift the same in a direction in opposition to the suction operated device.

3. In a carburetor, a casing, a throttle valve for controlling the volume of air entering the casing, a movable draft actuated element disposed in the path of travel of the draft passing through the casing, means for introducing fuel into the casing inwardly of the throttle valve and operated by the draft actuated element, a spring to move the draft actuated element in opposition to the action of the draft, and mechanical connecting means between the throttle valve and the draft actuated element so that the draft actuated element may be moved positively in the direction of the draft by the movement of the throttle valve.

4. In a carburetor, a casing, a throttle valve for controlling the volume of air entering the casing, a movable draft actuated element disposed in the path of travel of the draft passing through the casing, means for introducing fuel into the casing and operated by the draft actuated element, a spring to move the draft actuated element in opposition to the action of the draft, a lost motion mechanical connection between the throttle valve and the draft actuated element and adapted to shift the draft actuated element in the direction of the draft when the throttle valve is opened and to permit of the movement of the draft actuated element in the direction of the

draft without moving the throttle valve, and manually operated means to move the draft actuated element in opposition to the spring.

5. In a carburetor, a casing, a throttle valve to control the entrance of air into the casing, a block arranged between the outlet end of the casing and the intake manifold, said block having a main passage in communication with the interior of the casing, said block having a fuel supply port, means for mixing air and a liquid fuel and supplying the mixture to the port, a pivoted valve body carried by the block and disposed at the outlet end of the fuel supply port and having a port adapted to be turned into communication with the fuel supply port, a draft actuated element disposed within the main passage of the block and connected with the pivoted valve body, and means to move the draft actuated element in opposition to the action of the draft.
10. In a carburetor, a casing, a throttle valve to control the entrance of air into the casing, a block arranged beneath the outlet end of the casing, said block having a main passage in communication with the interior of the casing and also having a fuel supply port, an air inlet for the port, a receptacle to hold a liquid fuel, means of communication between the port and the receptacle including a tube extending into the receptacle below the level of the liquid fuel therein, means for supplying the liquid fuel to the receptacle, a pivoted valve body having a port to be moved into and out of communication with the first named port, and a draft actuated element connected with the pivoted valve body.
15. In a carburetor, a casing, a throttle valve to control the entrance of air into the casing, a block arranged beneath the outlet end of the casing, said block having a main passage and a fuel supply port and a moisture supply port, means to supply a fuel to the fuel supply port, means to supply air laden with water to the moisture supply port, a pivoted valve body having a port for coaction with the fuel supply port and a port for coaction with the moisture supply port, and a draft actuated element connected with the valve body.

20. In a carburetor, a casing, means to supply a fluid to the interior of the casing including a pivoted valve body, a draft actuated element connected with the pivoted valve body to turn therewith and adapted to be swung in one direction by the draft passing through the casing, means to move the draft actuated element in an opposite direction in opposition to the draft, a choke lever pivotally connected with the valve body and adapted to swing the draft actuated element in the direction of the draft and incapable of being moved by the valve body when the draft actuated element is shifted in the direction of the draft by such draft, and a throttle valve for controlling the volume of air passing through the casing.

25. In a carburetor, a casing, means to supply fuel to the interior of the casing including a pivoted valve body projecting into the bore of the casing, a draft actuated element bodily mounted upon the pivoted valve body to turn therewith and to be swung in one direction by the draft passing through the casing, a lever attached to the valve body to move therewith, means to move the lever in a direction to swing the draft actuated element in opposition to the travel of the draft, a choke lever pivoted upon the valve body and having a part to engage with the first named lever so that the choke lever may swing the draft actuated element in the direction of travel of the

30. draft, and a throttle valve for controlling the volume of air passing through the casing.

35. In a carburetor, a casing, means to supply a fluid to the interior of the casing including a pivoted valve body having its axis of turning movement extending transversely of the bore of the casing, a draft actuated element bodily mounted upon the pivoted valve body to turn therewith and to be swung in a direction longitudinally of the bore of the casing and to be moved in one direction by the travel of the draft through the casing, automatic means to move the draft actuated element in an opposite direction in opposition to the direction of travel of the draft, manually operated means to move the draft actuated element in the direction of travel of the draft, and a throttle valve to control the volume of air passing through the casing.

40. In a carburetor, a casing, means to supply fuel to the interior of the casing including a pivoted valve body having its axis of turning movement extending transversely of the longitudinal axis of the bore of the casing, a draft actuated element bodily mounted upon the pivoted valve body to turn with it and arranged within the bore of the casing to be swung longitudinally of the bore in one direction by the travel of the draft through the casing, automatic means to move the draft actuated element in an opposite direction in opposition to the action of the draft, and a throttle valve to control the volume of air passing through the casing.

45. In a carburetor, a casing, a throttle valve for controlling the entrance of air into the casing, a draft actuated element disposed in the path of travel of the draft passing through the casing and adapted to move to a position to close the passage through said casing, means for introducing fuel into the casing inwardly of the throttle valve and operated by the draft actuated element, a suction operated device leading into the casing at a point inwardly of the air controlling throttle valve and between the air controlling throttle valve and the draft actuated element, and means connecting the suction operated device with the draft actuated element, such suction operated device serving to move the draft actuated element toward its closed position.

50. In a carburetor, a casing, a throttle valve for controlling the entrance of air into the casing, a movable draft actuated element disposed in the path of travel of the draft passing through the casing, means for introducing fuel into the casing inwardly of the air controlling throttle valve and including a valve element for controlling the volume of fuel entering the casing, said valve element being operated by the draft actuated element, means to move the draft actuated element in opposition to the action of the draft, means connected with the air controlling throttle valve and actuated by the same when the throttle valve is moved toward the open position to positively operate the valve element for supplying fuel into the casing, such positively operating means permitting of the further opening operation of the said valve element without moving the air controlling throttle valve toward the open position, and manually operated means for actuating the said valve element for supplying fuel into the casing while the air controlling throttle valve is substantially closed.

55. In a carburetor, a casing, a throttle valve for controlling the entrance of air into the casing, a movable draft actuated element disposed in the path of travel of the draft passing through

the casing, means for introducing fuel into the casing inwardly of the throttle valve and including a valve element for controlling the volume of fuel entering the casing, said valve element being operated by the draft actuated element, means to move the draft actuated element in opposition to the action of the draft, means operated by the

air controlling throttle valve when it is moved toward the open position to actuate the valve element to supply fuel to the casing, and separate means to actuate the said valve element to supply fuel into the casing without moving the air controlling throttle valve.
